COMPENSATOR FOR RIVETING MACHINES

Wilbur Johndrew, Buffalo, N. Y.

Application September 22, 1944, Serial No. 555,366

12 Claims. (Cl. 78—48)

My invention relates in general to compensators and particularly to devices for determining the height of rivet heads and is used in connection with the control means of a riveting machine to terminate the riveting action of such a machine at a predetermined point in the riveting operation.

It is well known to those skilled in the art, that, in some riveting machines, the height of the rivet head is determined by the overall length of the rivet at the completion of the riveting action. Obviously should there be any variation in the thickness of the workpieces being riveted or variations in the proportions of the rivet, the height of the rivet head will be definitely affected. It is also well known that such variation is prohibitive in certain industries, such, for instance, as the airplane industry, and it is of the utmost importance that the formed rivet head have a definite predetermined thickness, irrespective of any of the variations above mentioned.

The principal object of my invention, therefore, has been to provide a thickness compensator whereby variations in workpiece or rivets may be compensated for, and the head of the rivet accurately formed by predetermining the thickness thereof.

Another object has been to provide a device of this nature which may be used as an accessory to a riveting machine and be easily attached to or detached therefrom.

Moreover, my device is provided with sensitive adjusting means, whereby it may be set to produce a rivet head of a predetermined thickness.

Furthermore, graduations are provided on the adjusting means so that various size rivets may be logged numerically to avoid repeated trial for a rivet head size.

The above objects and advantages have been accomplished by the device shown in the accompanying drawings of which:

Fig. 1 is a front elevation of my device showing it attached to a riveting machine, a fragmentary portion only of the machine being shown;

Fig. 2 is an enlarged longitudinal sectional elevation of the preferred form of my invention, taken on line II—II of Fig. 4 and shown in circuit closing position with an upset rivet in place;

Fig. 3 is a sectional plan view thereof, taken on line III—III of Fig. 2;

Fig. 4 is a reduced sectional plan view thereof, taken on line IV—IV of Fig. 2;

Fig. 5 is a reduced sectional plan view, taken on line V—V of Fig. 2;

Fig. 6 is a fragmentary sectional elevation of a modified form of the invention, taken on line VI—VI of Fig. 7; and,

Fig. 7 is a bottom plan view of the invention of Fig. 6, taken on line VII—VII of Fig. 6.

Referring to Fig. 1, I show the upper portion 10 and the lower portion 11 of a riveting machine. 10 These portions are located at the throat of the machine, and the upper portion of the machine carries the riveting ram 12 to which is attached the movable anvil 13. The portion 11 of the machine carries the usual height control screw 14 to which the stationary anvil 15 is secured by the stud 16, in well known manner. Suitable means (not shown) are of course provided on the riveting machine for causing the ram to descend and coact with the stationary anvil during the riveting operation.

My device comprises in general a pressure sleeve 20 which is slidably mounted upon the stationary anvil 15 and which is kept normally in its upper position by means of a pressure sleeve spring 21. This spring is mounted beneath the sleeve, having one end contacting with the lower surface thereof, and the other end engaging the flange 22 of the anvil 15. As shown in Fig. 2, to which reference is made, the pressure sleeve is shown as having been moved downwardly to the position where the gap 17 between its upper edge and the upper end of the anvil is substantially the same height as the desired thickness of the rivet head, at which time 30 the action of the ram 12 will be terminated. In order to prevent the sleeve from being moved upwardly on the stationary anvil beyond a predetermined point, a spline pin 23 is provided. This pin is carried by and extends laterally 40 through the pressure sleeve and engages a longitudinally extending flattened surface 24 formed on the stationary anvil 15. Not only does this spline pin together with the flattened surface 45 limit the endwise movement of the pressure sleeve upon the anvil 15, but it also prevents rotation of the sleeve upon the anvil for reasons to be hereinafter described.

The sleeve is provided on its lower end with a 50 collar 25 having a series of equidistantly spaced detent grooves 26 formed longitudinally in its surface. The sleeve is furthermore provided with screw threads 30 for the reception of the casing 31 of the device. This casing is preferably formed with a casing head 32 which is pro-

vided with interior screw threads for cooperation with the screw threads 30 of the sleeve. The casing is also provided with a skirt 33 having an inner flange 34 at its lower end, thus providing an upwardly facing shoulder 35. The casing head 32 is formed with a radially arranged bore 36 extending inwardly toward the stationary anvil and carries a detent ball 40 for engagement with any one of the detent grooves 26 formed in the pressure sleeve. The detent ball is pushed inwardly and held in contact with the sleeve by means of a helical spring 41, mounted within the bore. The casing 31 may thus be rotated upon the pressure sleeve definite and predetermined amounts, the screw threads 30 serving to move the casing axially upon the sleeve to adjust its position relatively thereto in order to determine very accurately the place in the riveting operation where the head will have reached its predetermined height. Graduations 39 are preferably provided on the casing whereby the device may be logged for various size rivets. As hereinbefore stated, the spline pin 23 prevents relative rotation of the sleeve 20 upon the anvil 15 so that the above adjustments may be conveniently made.

Carried by the anvil flange 22 is a collar 42 which is formed with an inwardly projecting flange 43 for engagement with the upper surface of the flange 22. The collar 42, shown in Fig. 3, is preferably split at 47, the ends being clamped together by means of a screw 44, whereby the collar is securely attached to the anvil flange. The flange 43 extends part way across the collar and carries a stud ring 45 of insulating material. This ring is preferably secured to the flange by means of countersunk screws 46. Carried by the stud ring 45 are three contact studs 50, preferably equidistantly spaced, and secured in place by means of countersunk screws 51. Only two studs 50 are required as live contacts, but three of them are used so as to provide adequate contact with a contact ring 52. This contact ring is mounted above the studs and is carried by and secured to a pressure ring 53 by means of countersunk screws 54. This pressure ring is of insulating material and is mounted to float within the casing 31. The ring is pushed downwardly by means of a plurality of helical springs 55 having their upper ends mounted in recesses 56 formed in the casing head 32 and their lower ends mounted in recesses 60 formed in the ring 53. The pressure ring 53 is of such a diameter as to engage the shoulder 35 of the casing skirt 33 when the pressure sleeve is in its upper position. The sleeve is pressed upwardly and maintained normally in its upper position by means of the spring 21, as hereinbefore described. The springs 55 serve to maintain the pressure ring normally in contact with the shoulder 35. When, however, the pressure sleeve 20 is forced downwardly, as will be hereinafter described, the pressure ring 53 will be carried down with it as a unit, until such time as the contact ring 52 contacts the contact studs 50. As will be clear to those skilled in the art, there is likely to be a slight overtravel of the anvil 13 and the riveting ram 12 after the ring 52 has made contact with the contact studs, and to compensate for this overtravel, the springs 55 will permit the sleeve to travel downwardly after movement of the ring 52 has been stopped thus preventing damage to the device. This amount of overtravel is of course compensated for in the adjustment of the device for any given rivet head height.

So as to enclose the space between the skirt 33

of the casing and the collar 42, a lower casing 61 is provided. This casing is circular in form and is suitably secured to the flange 43 of the collar and the stud ring 45. This casing extends upwardly within the skirt 33 of the casing 31, and is preferably formed with an opening 62 for the reception of the electrical conduit 63 carrying current to the device. This conduit passes through a suitable aperture (not shown) formed in the collar 42, and it is preferably retained in position by means of a clamp collar 64 held in place by means of a set screw 65 carried by the collar 42. So as to conduct electricity to two of the contact studs 50, contact arms 66 are provided, each of which is secured under one of the studs, as shown in Fig. 4, and leads 70 from the conduit 63 are secured thereto, preferably by soldering.

When two sheets 67 shown in Fig. 2 are to be riveted together by means of my device, they are placed between the riveting anvil 13 and the pressure sleeve 20 resting upon the latter which is normally in its upward extended position. The operator causes the ram to be moved downwardly by well known means which causes the work-pieces to be pressed against the pressure sleeve causing it to move downwardly against the tension of the spring 21. This will bring the body part of the rivet in contact with the stationary anvil 15, and further downward movement of the riveting anvil 13 will bring about the upsetting of the rivet, as clearly shown in Fig. 2. The device is adjusted so that when the rivet head thus formed is of predetermined thickness, the contact ring 52 will engage the two live contact studs 50, thus closing the circuit (not shown) and stopping the operation of the ram. Should delay occur in the stopping of the riveting operation after the above mentioned circuit has been closed, the spring pressed ring 53 will compensate for such further movement of the pressure sleeve by moving upwardly in the casing 31 against the tension of the springs 55, as hereinbefore described. Owing to the convenient adjustability of my device, any such overtravel may be easily compensated for.

Referring now to the form of invention shown in Figs. 6 and 7, the stationary anvil is represented at 71 upon which is mounted the pressure sleeve 72. This sleeve is preferably formed integrally with a hollow casing 73, and is formed with a recess 74. Within the recess 74 is mounted an insulating ring 75 which is suitably secured in place and which carries the contact plates 76 of the device. These contact plates are made of resilient material suitably secured to the ring at one end and formed with contact tips 80 at their free ends. They are bent downwardly as shown in Fig. 6, and leads 81 coming from a conductor wire 82 are suitably secured under the plates to conduct electricity thereto.

The stationary anvil 71 is formed with the usual anvil flange 83 and the usual stud 84 for securing the anvil to the height control screw of the riveting machine. An anvil ring 85 is mounted upon the stationary anvil 71 and has a flange 86 which extends over and is permanently secured to the anvil flange 83. The outer periphery of this anvil ring is screw threaded for engagement with an adjusting ring 90. The adjusting ring is formed with an upstanding flange 91 within which is suitably secured a ring 92 of insulating material. Secured to the upper surface of the ring 92 is a contact ring 93 with which the points 89 of the contact plates 76 contact

when the pressure sleeve 72 is moved downwardly upon the stationary anvil 70, such contact being made at the end of the riveting operation. A helical spring 94 serves to keep the pressure sleeve normally in its upper position, as shown in Fig. 6. The adjusting ring 90 is preferably knurled so that it may be conveniently rotated upon the anvil ring 85, and graduations are provided so that its position may be indicated.

Obviously, when this form of my invention is to be used, the pressure sleeve 72 is forced downwardly upon the anvil 70 in a manner similar to the other form of invention, and when the sleeve has reached the point in its travel at which the device has been previously adjusted, the contact plate 76 will make contact with the contact ring 93 and stop the ram action. Any overtravel in this form will be compensated for by the resiliency of the contact plates 76.

While I have shown and described my device in detail, it is obvious that the inventive principles disclosed herein may assume other physical embodiments without departing from the spirit or scope of the invention set forth by the appended claims.

Having thus described my invention, what I claim is:

1. The combination in a riveting machine, having a stationary anvil and coacting movable anvil, of a compensator comprising a pressure sleeve mounted upon said stationary anvil for longitudinal movement thereon, spring means for keeping said sleeve in its normal upper position, a casing carried by said pressure sleeve, and contact means mounted within said casing and actuated upon downward movement of said pressure sleeve, said casing being adjustable axially relative to said sleeve for adjusting the normal distance between the contact means.

2. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, contact means mounted within said casing and actuated upon downward movement of said pressure sleeve, index means carried by the pressure sleeve and casing for permitting predetermined graduated axial adjustment of said casing on said sleeve, and means for adjusting the normal distance between the contact means.

3. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, contact means mounted within said casing and actuated upon downward movement of said pressure sleeve, index means carried by the pressure sleeve and casing for permitting predetermined graduated axial adjustment of said casing on said sleeve, spline means carried by said pressure sleeve and said stationary anvil for preventing relative rotation thereof, and means for adjusting the normal distance between the contact means.

4. The combination in a riveting machine, having a stationary anvil and a coacting movable anvil, of a compensator comprising a pressure sleeve mounted upon said stationary anvil

for longitudinal movement thereon, spring means for keeping said sleeve in its normal upper position, a casing carried by said pressure sleeve, a spring pressed contact ring carried by said casing, a plurality of contact members carried by said stationary anvil and engageable with said contact ring upon downward movement of the latter, and means for adjusting the casing axially upon the pressure sleeve to alter the relative position of the contact ring with respect to the contact members.

5. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, a spring pressed contact ring carried by said casing, a collar carried by said stationary anvil and located beneath said casing, a plurality of contact studs carried by said collar and engageable with said contact ring upon downward movement of the latter, and means for adjusting the casing axially upon the pressure sleeve to alter the relative position of the contact ring with respect to the contact studs.

6. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, a spring pressed pressure ring resiliently mounted in said casing, said casing having an inwardly extending flange forming a shoulder for engagement with said pressure ring to limit its downward movement within the casing, a contact ring carried by said pressure ring, a plurality of contact studs stationarily arranged with respect to the anvil and engageable with the contact ring at a predetermined point in the downward travel of said ring.

7. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, a spring pressed pressure ring resiliently mounted in said casing, said casing having an inwardly extending flange forming a shoulder for engagement with said pressure ring to limit its downward movement within said casing, a contact ring carried by said pressure ring, a collar carried by said anvil beneath said casing, a ring of insulating material carried by said collar, and a plurality of contact studs carried by said ring and engageable by said contact ring when the latter moves downwardly.

8. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, a spring pressed pressure ring resiliently mounted in said casing, said casing having an inwardly extending flange forming a shoulder for engagement with said pressure ring to limit its downward movement within said casing, a contact ring carried by said pressure ring, a collar carried by said anvil be-

neath said casing, a ring of insulating material carried by said collar, a plurality of contact studs carried by said ring and engageable by said contact ring when the latter moves downwardly, and means carried by said sleeve and said casing for adjusting the axial relationship of the casing upon the sleeve.

9. The combination in a riveting machine, having a stationary anvil and a coacting movable anvil of a compensator comprising a pressure sleeve mounted upon said stationary anvil for longitudinal movement thereon, spring means for keeping said sleeve in its normal upper position, a casing carried by said pressure sleeve, contact means mounted within said casing and actuated upon downward movement of said pressure sleeve, and a lower casing carried by said stationary anvil and in telescopic arrangement with said casing.

10. The combination in a riveting machine, having a stationary anvil and a coacting movable anvil, of a compensator comprising a pressure sleeve mounted upon said stationary anvil for longitudinal movement thereon, spring means for keeping said sleeve in its normal upper position, a casing carried by said pressure sleeve, a spring pressed pressure ring resiliently mounted in said casing, said casing having an inwardly extending flange forming a shoulder for engagement with said pressure ring to limit its downward movement within said casing, a contact ring carried by said pressure ring, a collar carried by said anvil and located beneath said casing, a ring of insulating material carried by said collar,

5 a plurality of contact studs carried by said ring and engageable by said contact ring when the latter moves downwardly, and a lower casing surrounding said ring of insulating material and extending up within the upper casing.

11. The combination in a riveting machine, having a stationary anvil and a coacting movable anvil, of a compensator comprising a pressure sleeve mounted for longitudinal movement upon said stationary anvil, spring means for maintaining said sleeve in its normal upper position, a casing carried by said sleeve, electrical contact plates enclosed within said casing, a contact ring carried by said stationary anvil for engagement by said contact plates, and means carried by said stationary anvil for adjusting said ring.

12. The combination in a riveting machine, having a stationary anvil and a coacting movable anvil, of a compensator comprising a pressure sleeve mounted for longitudinal movement upon said stationary anvil, spring means for maintaining said sleeve in its normal upper position, a casing carried by said sleeve, electrical contact plates enclosed within said casing, a contact ring carried by said stationary anvil for engagement by said contact plates, an adjusting ring carrying said contact ring and mounted on said stationary anvil, and means carried by said 20 adjusting ring and said anvil for moving said contact ring to adjust its axial relation to said anvil.

WILBUR JOHNDREW.
